LOUVER

Saul M. Ferman, Detroit, Mich., assignor to Bendix Aviation Corporation, Detroit, Mich., a corporation of Delaware

Application August 21, 1950, Serial No. 180,660

1 Claim. (Cl. 98—121)

1

This invention relates to a ventilator construction and more particularly to a simple and inexpensive louver which can be quickly and easily attached to a wall or chassis to provide optimum ventilation.

The louvers now in use are either integral with the walls which they ventilate or are attached to the walls. The integral louvers are usually formed in a stamping operation and are disadvantageous in that they are expensive to make and cannot be adjusted to provide optimum ventilation under varying conditions. The attachable louvers now in use are relatively complex and expensive and cannot be easily standardized. They require an expensive die for every given area of opening.

This invention provides a louver construction which is simple and inexpensive and which can be easily attached to a wall or chassis. The louver is adapted to be attached in a number of different ways to the wall or chassis so as to provide optimum ventilation as well as optimum weather protection under all conditions. The louver is suitable for use with a considerable number of apertures of different sizes.

An object of the invention is to provide a louver which can be quickly attached to a wall to furnish ventilation.

Another object of the invention is to provide a louver of the above character which can be easily standardized in a few different sizes so that the louvers can be purchased by the linear foot in the size desired.

A further object is to provide a louver of the above character which can be fastened to a wall in a number of different positions so as to furnish a maximum amount of protection against different weather conditions.

Still another object is to provide a louver which can be simply and inexpensively constructed.

Other objects and advantages will be apparent from a detailed description of the invention and from the appended drawings and claim.

In the drawings:

Figure 1 is a front elevational view of a wall before the louvers are attached;

Figure 2 is a front elevational view of the proposed louver;

Figure 3 is an enlarged sectional view of the louver taken substantially on the line 2—2 of Figure 4; and

Figure 4 is a perspective view from in front and above the wall, showing the louvers attached to the wall.

In one embodiment of the invention a wall 10

2

is provided. The wall has spaced cross strips 12 which define apertures 14. Spaced holes 16 are provided in each of the cross strips 12.

A plurality of louvers, generally indicated at 18, are adapted to be secured to the cross strips 12. Each of the louvers 18 has a plurality of flat heads 20 spaced at the same intervals as the cross strips 12. Each head 20 has a hole 22 and a rivet 24 extends through each hole 22 and the corresponding hole 16 in the cross strips 12 to secure the louver to the wall 10. The flat heads 20 of each louver are integrated with each other by a flat band 26 which extends in a transverse direction to a position above the heads 20. An offset portion 28 integral with the band 26 extends from each band at an angle such as 45°. Each offset portion 28 is in turn bent inwardly to form a lip 30 substantially parallel to the head 20 and the band 26. The lips 30 extend in a transverse direction to a position above the head 20 to provide one side of each head with a projecting portion.

The louvers are secured to the wall 10 in parallel relationship to one another, with the offset portions 28 being positioned adjacent the apertures 14. The louvers are preferably secured to the wall in abutting relationship, such that the portion projecting from each flat head 20 fits into the undercut portion in the corresponding flat head of the adjacent louver. Ventilation for the wall 10 is then provided by the opening between the offset portions 28 on each louver and the flat band 26 on the adjacent louvers.

The louver construction disclosed above has a number of advantages. The louvers can be easily attached to any wall in which the cross strips 12 have substantially the spacing of the flat heads 20. Thus, the size of the apertures 14 between the cross strips 12 may vary considerably by varying the width of the cross strips. The effective ventilation can also be varied by varying the height of the apertures 14 and accordingly varying the number of louvers attached to the cross strips.

The louvers may be standardized in a number of different sizes, each size having a predetermined spacing between adjacent flat heads 20. By employing standardized louvers, the louvers may be purchased by the linear foot in the size desired and at a price lower than the louvers now in use.

Depending upon the weather conditions, the louvers may be attached to the inside or outside surface of the wall 10 and with the offset portions 28 pointing upwardly or downwardly. Since the

louvers may be positioned in accordance with the weather conditions normally encountered in a particular location, they are adapted to provide a maximum amount of protection against such conditions as rain and wind-blown sand.

Although this invention has been disclosed and illustrated with reference to particular applications, the principles involved are susceptible of numerous other applications which will be apparent to persons skilled in the art. The invention is, therefore, to be limited only as indicated by the scope of the appended claim.

What is claimed is:

In combination, a wall member having an elongated opening intermediate its ends, the wall member also having a plurality of cross strips spaced from one another to provide apertures, there being a plurality of holes in each cross strip, a plurality of louvers extending in spaced parallel relationship across the apertures, each louver including, a plurality of completely flat heads spaced in accordance with the spacing of the cross strips, there being a hole in each flat head adapted to be aligned with a corresponding hole in its associated cross strip, means extending through the holes in the flat heads and cross

strips to attach the louvers to the wall member, a plurality of flat bands joining the flat heads, and an offset portion extending from each flat band at a predetermined angle to the flat band to provide a ventilation opening through the wall, the flat bands and offset portions defining on each flat head a projection at one side and an undercut at the opposite side to provide an interleaving of the flat heads on the different louvers when the louvers are attached to the cross strips in abutting relationship.
